US00D829283S

(12) **United States Design Patent** (10) **Patent No.:** **US D829,283 S**
(45) **Date of Patent:** **** Sep. 25, 2018**

(54) **QUADCOPTER**

(71) Applicant: **Guangdong Meijixin Innovation and Technology Co., Ltd.**, Chenghai, Shantou (CN)

(72) Inventor: **Zhaohan Cai**, Shantou (CN)

(73) Assignee: **Guangdong Jeijixin Innovation and Technology Co., Ltd.**, Shantou (CN)

(**) Term: **15 Years**

(21) Appl. No.: **29/571,429**

(22) Filed: **Jul. 18, 2016**

(51) **LOC (11) Cl.** **21-01**

(52) **U.S. Cl.**

USPC **D21/441**

(58) **Field of Classification Search**

USPC D12/16.1, 319-345; D21/436, 441, 442, D21/443, 444, 447-454

It is certified that error appears in the above-identified patent and that said Letters Patent is hereby corrected as shown below:

On the Title Page

Item (73) naming the Assignee currently reads:

(73) Assignee: Guangdong Jeijixin Innovation and Technology Co., Ltd., Shantou (CN)

And should read:

(73) Assignee: Guangdong Meijixin Innovation and Technology Co., Ltd., Shantou (CN)

Signed and Sealed this
Eighteenth Day of February, 2020
